(57) **CLAIM**

We claim the ornamental design for an anterior antenna casing for a magnetic resonance imaging receive coil, as shown and described.

DESCRIPTION

FIG. 1 is a back perspective view of an anterior antenna casing for a magnetic resonance imaging receive coil;

FIG. 2 is a left side view thereof;

FIG. 3 is a right side view thereof;

FIG. 4 is a front view thereof;

FIG. 5 is a back view thereof;

FIG. 6 is a top view thereof; and,

FIG. 7 is a bottom view thereof.
